DETECTING DEVICE

Maurice Elie Nahmias, 13 Rue Colbert, Chatenay-Malabry, France

Filed Mar. 26, 1957, Ser. No. 648,662

6 Claims. (Cl. 250—43.5)

This invention relates to devices for detecting smoke and/or radio-active gases, and which may in certain cases also be used for detecting light or flame or the presence of intruders.

The ionizing properties of electromagnetic and corpuscular radiations are well known and it is also known that smoke can cause recombination of the ions whereby the ionization current produced by a radio-active source is diminished. This property has already been used in smoke-detecting apparatus.

United States Patent No. 2,702,898 describes the most developed form of this type of apparatus. This detector, however, has disadvantages which it is the object of the present invention to overcome.

In particular, one disadvantage is the use which has been proposed of more than one radioactive source, since the physico-chemical evolution of a plurality of sources, as a function of time, will be different and will influence the penetration of radium salt in each of the source carriers so as to modify the alpha emissions.

A second defect is due to the fact that the radioactive source of known detectors in the test chamber is continuously under the action of the surrounding air and dampness and dust which accumulate on the source and influence the alpha emission of the source.

A third reason for possibly defective operation is due to the poor insulation of the flange which separates the test-chamber from the comparison chamber. In fact, like the test chamber, this flange is in direct and continuous contact with the surrounding air which deposits conducting matter on the flange. Moreover, this flange is not accessible without partly dismantling the device, so that cleaning can be done only by a skilled person familiar with its construction.

Finally, this detector is constructed so as to be sensitive to drafts and the false alarms which it commonly gives can probably be attributed to the consequent movement of ions in the test chamber.

The aforesaid United States patent describes a device having only a single source of alpha rays confined between 2 thin foils and causing a symmetrical ionization in each of two chambers located on each side of the source. This symmetrical ionization in both chambers is unfavorable for smoke detection.

In contradistinction thereto, the present invention provides a pair of adjacent chambers, a single source of alpha-particles sheltered from dust and located to cause an asymmetrical ionization in gases contained in said chambers, means to pass current through said ionized gases, means sensitive to the difference between the currents in each chamber to provide a signal if said difference exceeds a predetermined value, and means for the introduction of the gas to be monitored into one of said chambers.

A preferred form of smoke-detecting device will now be described with reference to the accompanying diagrammatic drawing in which:

Figure 1 illustrates the device in vertical section, and Figure 2 is a section of a part of the device.

2

The device includes two ionization chambers I and II formed by a metal housing 1 having side walls 2 and opposite parallel end walls 3 and 4; the housing is divided approximately equally by a wall W comprising a window 5 including a very thin foil M, or possibly two thin foils, the foil or foils having a thickness equivalent to 1 cm. of air and being supported between a pair of grids g_1 and g_2 , mounted in central circular apertures in plates x_1 and x_2 , whereby rupture of the foil is prevented as well as vibrations which might cause a variation of capacity and give a false alarm.

A single radio-active source S, preferably an alpha particle source of 10μ c. intensity, is carried by a stem 5 extending symmetrically through an insulating insert i_3 15 positioned centrally on the housing end wall 3, the stem being slideable axially in the insert. The chamber I is provided with two small holes O_1 and O_2 , which are such as to allow conditions within chamber I to conform to those of ambient air while the source is protected from 20 dust and the like.

An electrode E_1 , which is maintained at a potential $+V_1$ by the circuit indicated, extends into the chamber through an insert i_1 of insulating material in a side wall 2 of the housing. The chamber II is provided with an 25 electrode maintained at a negative potential V_2 , which electrode E_2 extends through an insert i_2 of insulating material, also in a side wall 2 of the housing.

The inserts are similar and are shown in detail in Figure 2: each comprises an apertured disc 20 through 30 which the electrode E_1 or E_2 or the stem 5 passes, a guard ring 21 of conducting material which is grounded in the operation of the device and surrounds the disc 20, and an outer ring 22 of insulating material surrounding the guard ring 21 and secured to the housing wall. It will be 35 appreciated that the guard rings are readily accessible and visible so that, when cleaning is necessary, it can be accomplished in a minimum of time by an unskilled person without need for dismantling the device.

With the device illustrated (in that form which will be 40 called the "dynamic" form of the device), it is desired to continuously monitor gas from a remote point and two insulated tubes t_1 and t_2 are connected to the chamber II opposite one another, one of the tubes extending to the remote point and the other acting as an outlet.

A modification of the device illustrated (in that form 45 which will be called the "static" model) is designed to monitor the gas surrounding the device; the tubes are dispensed with and the side walls of chamber II are perforated.

The housing 1 is electrically connected by means of the 50 conducting coil L with the electrode G of a cold cathode triode 6; the coil extends through a central hole in a block of transparent insulating material p_1 , such as Lucite, at the base of the chambers which shields them against outside deteriorating influence.

The ionization current of the chamber I is fixed at a 55 value I_1 higher than the current I_2 of the chamber II, by adjusting the potentials $+V_1$ and $-V_2$ and the position of the source S for a given thickness of the foil M. The two ionization currents are in opposition and the 60 value $(I_1 - I_2) = I_3$ must be such that the voltage at the terminals of a resistance R in the associated circuit, $V_3 = RI_3$, is normally smaller than the value V_4 of the voltage required to trigger the cold cathode tube 6 between G and K, which would then cause a discharge between A and K. When smoke comes into the chamber 65 II, the current I_2 decreases, I_3 and V_3 increase and the cold cathode triode 6 triggers between G and K; current then passes between the anode A and the cathode K, which energizes the relay coil E and thereby operates the 70 buzzer or alarm B.

Cold cathode tubes have been heretofore used for the

measurement of very small ionization currents, e.g. by Mutschuller (U.S. Patent No. 2,036,072) and Ernest Franklin (British Patent No. 638,833), and suitable cold cathode tubes are available, such as the WL759 which is sensitive to currents of smaller than 10^{-9} amperes and was used in the Mutschuller device.

The use of two asymmetrical ionization chambers with a single radio-active source is an important characteristic of the invention. This asymmetry, which is particularly favorable to smoke detection, is due to the shape of the ionization curve of an alpha particle emitter, called Bragg's curve, which shows three parts: the first shows a constant ionization along the path of the alpha particles until about 1 cm. from the end of their path. The second part shows a sudden ascent of the ionization current near the end of the path. Finally, the third part shows an almost vertical fall of the ionization in the last 3 mm. or so of the alpha particles' path. The present invention takes advantage of the shape of this curve for producing the asymmetrical ionization conditions in the chambers I and II. The chamber I works on the constant part of the ionization curve whereas chamber II works on the variable part which is very sensitive both to ion recombination and density changes.

The device according to the invention can be used for the detection of radio-active gases. If the place to be monitored contains a radio-active gas, the ionization current in the chamber II, instead of decreasing, will increase and will be able in certain cases, where alpha emanations are present, to give a current I_2 higher than I_1 and to produce at the terminals of the resistance R a potential difference higher than V_4 , whereupon an alarm will be given. Better sensitivity is obtained (with the danger, however, of contamination of the source S) by screwing the pipes t_1 and t_2 in the holes O_1 and O_2 and by circulating the gas suspected of containing radio-active gases through the chamber I. The current I_1 will increase due to the radio-active gases and will raise the values of I_3 and V_3 , and this will give the alarm with a better sensitivity than is obtained with the usual ionization chamber which is not coupled to a second ionization chamber in opposition as is the case in accordance with the invention.

The cold cathode triode is normally surrounded by a metal cylinder H_1 snugly received in a recess in the insulating block p_1 ; within the cylinder are mounted two opaque disc-like masks H_2 and H_3 on either side of the cold cathode triode and at the end of the cylinder opposite the block p_1 there is secured a disc p_2 of transparent insulating material. If the masks H_2 and H_3 are taken off, and a cold cathode triode sensitive to light is used, such as the GK50 (Ferranti), the block p_1 , and disc p_2 of transparent insulating material act to "pipe" light to the cold cathode triode. If the whole device is regulated and put in darkness, any flame or light triggers the cold triode, provided the potential on its grid G, in darkness, has been regulated (by moving the source S) to a value V_3 suitably smaller than the triggering potential V_4 , e.g.: $V_3 - V_4 < 10$ volts.

In normal use, for the detection of smokes, radioactive gases, and flames (or light), the whole device is surrounded by a screen in order to avoid alarms in case of inadvertent grounding of the chambers I or II.

If the screen is removed the device will indicate as a result of the grounding of either of the chambers the presence of an intruder, whether man or animal. Any outside contact with the chambers I or II is sufficient to trigger the triode and give the alarm. The effectiveness of the device can be increased by connecting, to the chambers I and II, metallic wires, grids, doors and window handles, contacts under carpets, and so forth which are conveniently insulated and will be grounded by contact with the "visitor." The ground connection will cause the triggering of the cold cathode triode and will give the alarm.

What I claim is:

1. A detector device comprising a housing defining two adjacent chambers and including an intermediate wall separating the chambers, a window means supported in the intermediate wall, a single source of radiation energy supported in one of the chambers and radiating through said window means into the other of the chambers, electrodes positioned respectively in said chambers, one of the chambers being coupled to ambient air and the other chamber being coupled to a medium to be monitored, the asymmetrical arrangement of said source with respect to said chambers causing an unequal distribution of ionization current at said electrodes, a utilization means, and an electric circuit coupling said electrodes to said utilization means so that the normal unequal distribution of the current renders the utilization means ineffective, the presence of the medium in said other chamber redistributing the current at the electrodes to render the utilization means effective.
2. A device as claimed in claim 1, wherein said source of radiation energy is a source of alpha particles, said window means comprising a foil for the passage of said particles and a grid means encompassing said foil for the support thereof against shock and vibration.
3. A detector device comprising means defining a pair of adjacent chambers, a single source of alpha particles positioned asymmetrically with respect to said chambers to cause asymmetrical ionization in gases contained in both said chambers, means operatively disposed with respect to the first said means to pass current through the ionized gases, means sensitive to the difference between the currents in each chamber to provide a signal with said difference exceeding a predetermined value, means coupled to the first said means for the introduction of the medium to be monitored into one of said chambers, and an intermediate member transparent to alpha radiation separating the chambers, the source of alpha particles being located in one chamber to direct radiation into the other chamber through said member, the second said means comprising: an electrode in each chamber, means applying to the electrodes potentials of opposite sign, a conductor coupled to the first said means to collect ions from both chambers, and an electrical circuit coupling the conductor with the signal providing means.
4. A device as claimed in claim 3, wherein the alpha particle source is positioned so that each alpha particle emitted from said source of alpha particles that ionizes the gas to be monitored in one of said chambers also passes through the other of said chambers.
5. A device as claimed in claim 3 wherein the chamber containing the source communicates with ambient air so as to permit slow diffusion only, the chamber remote from the source being adapted for introduction of said gas to be monitored.
6. A device as claimed in claim 3, wherein the first said means is a housing of metal and having side walls and opposite parallel end walls, said intermediate member dividing the housing approximately equally and including a thin metal foil rigidly supported in parallel to the end walls, said device further comprising a stem, and a plurality of insulating inserts in said housing, the source of alpha particles being supported by said stem which extends through one of said insulating inserts in one end wall, said pair of electrodes extending through the other insulating inserts, one electrode being positioned in each chamber, each said insert comprising two rings of insulating material and a conducting ring between the first said rings.
